UNITED STATES PATENT OFFICE.

ANTON E. OLSEN, OF NEW YORK, N. Y., ASSIGNOR OF ONE-HALF TO GEORGE M. REICHENBACH, OF NEW YORK, N. Y.

WINDOW-OPERATING DEVICE.

Application filed August 12, 1922. Serial No. 531,357.

To all whom it may concern:

Be it known that I, ANTON E. OLSEN, a citizen of the United States, and residing at New York, in the county of New York and State of New York, have invented certain new and useful Improvements in Window-Operating Devices, of which the following is a specification, such as will enable those skilled in the art to which it appertains to make and use the same.

This invention relates to window operating devices, and particularly to devices of this class designed for raising and lowering the windows or window panels of motor vehicles, and the object of the invention is to provide a novel lever and counterbalanced construction, by means of which the window panels may be easily and positively raised and lowered; a further object being to provide a device of the class specified of unitary construction to facilitate its mounting in connection with a suitable support; and with these and other objects in view, the invention consists in a device of the class and for the purpose specified, which is simple in construction, efficient in use and which is constructed as hereinafter described and claimed.

The invention described and claimed herein is an improvement on that shown and described in a co-pending application, filed January 30, 1922, Ser. No. 532,603, and is fully disclosed in the following specification, of which the accompanying drawing forms a part, in which the separate parts of my improvement are designated by suitable reference characters in each of the views, and in which:—

Fig. 1 is a view showing a part of a window framework, with one of my improved operating devices mounted in connection therewith.

Fig. 2 is a partial section on the line 2—2 of Fig. 1 and on an enlarged scale; and,

Fig. 3 is a partial section on the line 3—3 of Fig. 2.

In the drawing, I have diagrammatically indicated at 5, a part of a framework of a motor vehicle in which a window panel 6 is movably mounted, said framework being provided with a transverse strip 7 having an aperture 8 through which the window panel is movable. The window panel 6 is provided at its lower edge with a metallic strip 9 carrying at its opposite

sides of said panel, tracks or runways 10 in which roller bearings 11 mounted on the free ends of levers 12 are movable. The other ends of the levers 12 are mounted in a common pivot 13 secured to an attaching plate 14 and adjacent to the pivoted end, the levers are provided with elongated apertures 15 in which pins 16 are movable and the pins 16 are secured to a slide 17 mounted to move vertically on the attaching plate 14 and the upper end thereof being provided with a threaded block 18, through which a screw shaft 19 passes. A rod 20 is mounted in connection with the attaching plate 14 and mounted thereon is a spiral compression spring 21 which is adapted to cooperate with a spring seat 22 on the slide 17.

The upper end of the attaching plate 14 is enlarged and provided with a cup-shaped housing 23 in which is mounted a pin 24, on which is rotatably mounted a bevel gear 25, which meshes with a pinion 26 on the screw shaft 19, and the gear 25 is provided with an angular extension 27 which passes into a corresponding aperture in a crank 28. A yoke 29 is mounted on the pin 24 within the housing 23 and into which the upper end of the screw shaft 19 passes, and which forms a bearing and support for said shaft.

In the position of the parts of my improved operating device as shown in full lines in Fig. 1 of the drawing, the window panel 6 is in fully open position and when it is desired to raise or close said window panel, the crank 28 is rotated in the proper direction and the levers 12 are first moved outwardly, and then inwardly in the tracks or runways 10, and the spring 21 will operate to balance said window panel, the same operating to aid in the lifting or raising of the window and to support the window in its downward movement in which operation, said spring is compressed. Other springs 30 are connected to the slide 17 and to the levers 12 for aiding in this operation, but these springs may or may not be employed. They will however aid in carrying the levers 12 over what might be regarded as a dead center position, when said levers are both extended laterally in a horizontal position.

It will be apparent that my improvement is designed particularly for use in raising comparatively wide window panels, such as

the panels employed in connection with the body structure of a motor vehicle or the like, and while I have shown certain details of construction for carrying my invention 5 into effect it will be understood that I am not necessarily limited to these details and various changes therein and modifications thereof may be made within the scope of the appended claims without departing from 10 the spirit of my invention or sacrificing its advantages.

Having fully described my invention, what I claim as new and desire to secure by Letter Patent, is:—

15 1. A window operating device of the class described, comprising an attaching plate, levers pivotally mounted in connection with said plate and the free ends thereof being provided with antifrictional devices 20 adapted to cooperate with the window panel to be operated, a slide movably mounted in connection with said attaching plate and provided with parts cooperating with said levers and movable longitudinally thereof, 25 a screw shaft in threaded engagement with said slide and by means of which said slide is operated, and means for rotating said screw shaft.

2. A window operating device of the class 30 described, comprising an attaching plate, levers pivotally mounted in connection with said plate and the free ends thereof being provided with antifrictional devices adapted to cooperate with the window panel to be 35 operated, a slide movably mounted in connection with said attaching plate and provided with parts cooperating with said levers and movable longitudinally thereof, a screw shaft in threaded engagement with 40 said slide and by means of which said slide is operated; means for rotating said screw shaft, and a compression spring cooperating with said slide for counterbalancing said window panel in the operation of raising and lowering the same.

3. A window operating device of the class 45 described comprising an attaching plate, levers pivotally mounted in connection with said plate and the free ends thereof being provided with antifrictional devices adapted to cooperate with the window panel to be 50 operated, a slide movably mounted in connection with said attaching plate and provided with parts cooperating with said levers and movable longitudinally thereof, a screw shaft in threaded engagement with 55 said slide and by means of which said slide is operated, means for rotating said screw shaft, a compression spring cooperating with said slide for counterbalancing said window panel in the operation of raising and lowering the same, and other tensional devices connecting said levers with said slide.

60 4. A window operating device of the class

described, said device being of unitary construction and comprising an attaching plate, a bevel gear rotatably mounted in connection with said plate, means for rotating said gear, a screw shaft adapted to be rotated by said gear, a slide in threaded engagement with said screw shaft and actuated thereby, laterally disposed levers pivoted to said attaching plate and provided adjacent to the pivoted ends thereof with elongated apertures, said slide being provided with projecting elements extending through and adapted to operate in said apertures, and the free ends of said levers being provided with antifrictional devices. 70

5. A window operating device of the class described, said device being of unitary construction and comprising an attaching plate, a bevel gear rotatably mounted in connection with said plate, means for rotating said gear, a screw shaft adapted to be rotated by said gear, a slide in threaded engagement with said screw shaft and actuated thereby, laterally disposed levers pivoted to said attaching plate and provided adjacent to the pivoted ends thereof with elongated apertures, said slide being provided with projecting elements extending through and adapted to operate in said apertures, the free ends of said levers being provided with antifrictional devices, and a compression spring cooperating with said slide. 80

6. A window operating device of the class described, said device being of unitary construction and comprising an attaching plate, a bevel gear rotatably mounted in connection with said plate, means for rotating said gear, a screw shaft adapted to be rotated by said gear, a slide in threaded engagement with said screw shaft and actuated thereby, laterally disposed levers pivoted to said attaching plate and provided adjacent to the pivoted ends thereof with elongated apertures, said slide being provided with projecting elements extending through and adapted to operate in said apertures, the free ends of said levers being provided with antifrictional devices, a compression spring cooperating with said slide, and tensional devices connecting said levers and said slide. 90

7. A window operating device of the class described comprising two levers having a common fixed pivot, the free ends of said levers being provided with anti-frictional means cooperating with the window panel to be operated, a member movable relatively to the pivot of said levers, means on said member and in operative connection with said levers and movable longitudinally thereof for actuating said levers, and means for operating said member. 100

8. A window operating device of the class described comprising two levers having a common fixed pivot, the free ends of said levers being provided with anti-frictional 110

- means cooperating with the window panel to be operated, a member movable relatively to the pivot of said levers, means on said member and in operative connection with said levers and movable longitudinally thereof for actuating said levers, and means for operating said member, comprising a screw shaft in threaded engagement therewith.
- 10 9. A window operating device of the class described comprising two levers having a common fixed pivot, the free ends of said levers being provided with anti-frictional means cooperating with the window panel to be operated, a member movable relatively to the pivot of said levers, means on said member and in operative connection with said levers and movable longitudinally thereof for actuating said levers, means for operating said member comprising a screw shaft in threaded engagement therewith, a crank and gears for rotating said screw shaft and means for counter-balancing said window panel.
- 15 10. A window operating device of the class described comprising two levers having a common fixed pivot, the free ends of said levers being provided with anti-frictional means cooperating with the window panel to be operated, a member movable relatively to the pivot of said levers, means on said member and in operative connection with said levers and movable longitudinally thereof for actuating said levers, and means for operating said member comprising a screw shaft in threaded engagement therewith.
- 20

In testimony that I claim the foregoing as my invention I have signed my name this 10th day of August, 1922.

ANTON E. OLSEN.
